(57) **CLAIM**

The ornamental design for a barrette, as shown and described.

DESCRIPTION

FIG. 1 is a perspective view of a barrette showing my new design;

FIG. 2 is a side view thereof;

FIG. 3 is a top view thereof;

FIG. 4 is a bottom view thereof;

FIG. 5 is a front view thereof; and,

FIG. 6 is a back view of the invention.

The broken lines shown in FIGS. 1 and 2 are for illustrative purposes only and do not form part of the claimed design.
